UNITED STATES PATENT OFFICE.

JULIAN KENNEDY, OF PITTSBURGH, PENNSYLVANIA.

BLAST-FURNACE.

1,303,914.

Specification of Letters Patent. Patented May 20, 1919.

Application filed March 15, 1918. Serial No. 222,586.

To all whom it may concern:

Be it known that I, JULIAN KENNEDY, a citizen of the United States, residing at Pittsburgh, in the county of Allegheny and State of Pennsylvania, have invented a new and useful Improvement in Blast-Furnaces, of which the following is a full, clear, and exact description, reference being had to the accompanying drawings, forming part of

10 this specification, in which—

Figures 1 and 2 are elevations, at 90° to each other, of portions of a blast furnace structure embodying my invention.

Fig. 3 is a plan view of the same, and

15 Fig. 4 is a sectional view of the same showing two of the up-takes and a portion of one of the down-comer branches.

My invention has relation to blast furnaces, and more particularly to a novel construction and arrangement of the up-takes at the top of the furnaces and their manner of connection with the down-comer.

An object of my invention is to provide a construction and arrangement of the up-takes such as to prevent the discharge of an undue amount of the finer material in the burden or charge of the furnace. A further object of my invention is to provide a convenient and novel construction and arrangement of the up-takes and down-comer, such that the down-comer may be carried underneath the skip track.

Other objects of my invention will hereinafter appear.

35 In the accompanying drawing the numeral 2 designates a portion of the blast furnace structure, 3 the superstructure at the top of the furnace, 4 the skip track and 5 the dust catcher. These parts may be of any well known or suitable construction, as they

40 form no part of my present invention.

In accordance with my invention, I provide the top of the furnace with a plurality of up-takes 6 arranged in two pairs, at opposite sides of the furnace. 7 designates the down-comer, having a branch 8 with which one pair of the up-takes are connected, and another branch 9 with which the up-takes of the other pair are connected. The two up-takes of each pair are provided at their upper ends with restricted outlets 10 which are arranged to discharge into a common connection 11 of elbow-shape leading to one of the down-comer branches, as best shown in Fig. 4. It will be noted that both up-takes of each pair are connected behind the

corresponding branch of the down-comer, and that the general arrangement is such that the down-comer may readily extend across the furnaces underneath the skip track or bridge 4, with one of its branches extending upwardly at each side of said track or bridge. This, however, is not essential to the broader features of my invention.

I also preferably, but not necessarily, incline the up-takes 6 so that they are oblique to the vertical axis of the furnace. By reason of this inclination, the inner walls of the uptakes will act as baffles to catch and throw down a portion of the finer material forming the furnace burden of the charge, particularly in case of explosions. The discharge of such material is further limited by the restricted outlets 10 at the upper ends of the outlets. The combined effect of these two features of my invention is to throw back into the furnace a very considerable portion of fine charge material which would otherwise pass into the down-comer.

By placing both up-takes of each pair at the same side of the down-comer branch with which they connect, it will be readily seen that there will be no confusion of the draft currents in these connections, the discharge from both up-takes of each pair passing in the same direction into the down-comer.

The connections 11 are preferably made of gradually increasing cross sectional area to accommodate the added volume discharged from the inner uptake of each pair.

Each of these connections 11 may be provided with a suitable relief valve at 12.

I do not desire to limit myself to the particular construction and arrangement of the parts which I have herein shown and described, as it is obvious that the exact arrangement and method of connecting the up-takes and down-comer may be changed in various ways, without departing from the spirit and scope of my invention, as defined in the appended claims.

I claim:

1. A blast furnace having a plurality of uptake pipes extending above the top of the furnace proper, a down-comer, and a connection connecting the upper ends of the up-takes with the down-comers, said uptakes having restricted discharge openings leading into said connection, substantially as described.

2. A blast furnace having a plurality of uptake pipes extending above the top of the furnace proper, a down-comer, and a connection connecting the upper ends of the 5 uptakes with the down-comers, said uptakes having restricted discharge openings leading into said connection, and said uptakes extending in an oblique direction, substantially as described.
- 10 3. A blast furnace having a plurality of uptakes extending above the top of the furnace proper, a down-comer, and a connection connecting the upper ends of the 15 uptakes with the down-comer, said uptakes extending in an oblique direction, substantially as described.
4. A blast furnace having its up-takes arranged in sets connected at their upper ends to a common outlet connection, and a down- 20 comer to which said connection leads, all the up-takes of each set being arranged at the same side of the down-comer; substantially as described.
5. A blast furnace having its up-takes arranged in sets connected at their upper ends to a common outlet connection, and a down- 25 comer to which said connection leads, the up-takes having restricted outlets communicating with the said connection; substantially as described.
- 30 6. A blast furnace having a skip track or bridge, a down-comer extending underneath said track or bridge, a plurality of uptakes arranged in pairs at opposite sides of the furnace, and a common outlet connection for 35 each pair of the up-takes, each connection leading to a branch of the down-comer, and there being one branch of the down-comer at each side of the skip track or bridge; substantially as described.
7. A blast furnace having a skip track or bridge, a down-comer extending underneath said track or bridge, a plurality of up-takes arranged in pairs at opposite sides of the furnace, and a common outlet connection 45 for each pair of the up-takes, each connection leading to a branch of the down-comer at each side of the skip track or bridge, the up-takes having restricted outlets into said connections; substantially as described.
8. A blast furnace having a down-comer pipe provided with two diverging branches at its upper end and two pairs of uptakes extending upwardly from the top of the furnace proper, and a connection between the 50 upper ends of each pair of uptakes with one branch of the down-comer, substantially as described.

In testimony whereof, I have hereunto set my hand.

JULIAN KENNEDY.
